UNITED STATES PATENT OFFICE.

JOSEPH J. WALSER, OF ANN ARBOR, MICHIGAN, AND ALBERT A. HENZI, OF CHICAGO, ILLINOIS, ASSIGNORS TO GOSS PRINTING PRESS COMPANY, A CORPORATION OF ILLINOIS.

STEREOTYPE-PLATE-FINISHING MACHINE.

Application filed January 29, 1920. Serial No. 354,982.

To all whom it may concern:

Be it known that we, JOSEPH J. WALSER, a citizen of the United States, residing in Ann Arbor, in the county of Washtenaw and State of Michigan, and ALBERT A. HENZI, a citizen of the United States, residing in Chicago, in the county of Cook and State of Illinois, have invented certain new and useful Improvements in Stereotype-Plate-Finishing Machines, of which the following is a specification.

The invention relates to machines for finishing stereotype plates, and more particularly to a novel mechanism for clamping and unclamping the plates within the finishing machine prior and subsequently to the finishing operation.

Objects and advantages of the invention will be set forth in part hereinafter and in part will be obvious herefrom, or may be learned through practice with the invention, the same being attained through the instrumentalities and combinations pointed out in the appended claims.

The invention consists in the novel parts, arrangements, constructions, combinations and improvements herein shown and described.

The accompanying drawings, herein referred to and constituting a part hereof, illustrate one embodiment of the invention, and together with the description serve to explain the principles thereof.

Of the drawings:—

Fig. 1 is a side elevation of a plate finishing machine comprising an embodiment of the invention, and showing the mechanism in the plate locking position;

Fig. 2 is an end elevation, looking at Fig. 1 from the left;

Fig. 3 is a fragmentary detail end elevation of the plate clamping mechanism, which is shown near the center of Fig. 1 (and looking at Fig. 1 from the left) and at the right center of Fig. 2, showing the parts in plate locking position;

Fig. 4 is a similar view to Fig. 3, but showing the mechanism in the plate releasing position;

Fig. 5 is a detail elevation looking at Fig. 3 from the right;

Fig. 6 is a similar view looking at Fig. 4 from the right;

Fig. 7 is a view similar to Figs. 5 and 6, but showing the parts in an intermediate

position during the movement from the locking to the unlocking position;

Fig. 8 is a vertical section on line 8—8 of Fig. 3;

Fig. 9 is a vertical section on line 9—9 of Fig. 4;

Fig. 10 is a fragmentary detail elevation looking at the central part of Fig. 3 from the left;

Fig. 11 is a fragmentary detail elevation looking at the central part of Fig. 4 from the left; and

Fig. 12 is a fragmentary vertical section and elevation showing the mechanism for permitting and preventing the rotation of the cylinder.

The invention in certain of its aspects is directed to a rotary stereotype plate finishing machine wherein the stereotype plate to be finished is rotated past stationary or fixed but rotating trimming saws and past stationary or fixed shaving cutters. In certain of its aspects the invention is directed to a stereotype plate clamping and releasing mechanism which is controlled or brought into action by the starting of the machine itself into action. It will be understood, however, that in many of its features or aspects the invention is applicable to other forms of machines than the one herein shown and described as the present preferred embodiment of the invention.

Referring to the accompanying drawings, illustrating by way of example one embodiment of the invention, it is shown applied to and constituting a part of a stereotype plate trimming machine, in which machine the cast plate is received with the tail or riser attached thereto, and forming or projecting from one of the arcuate ends of the plate, just at it comes from the casting machine. This plate is slid endwise into the interior of the cylindrical body of the trimming machine, the plate sliding upon its straight edges upon tracks or guides located longitudinally and very nearly centrally within the cylinder. As the plate runs or slides in upon the guides, it fits loosely within the cylinder, the convex or printing surface on the exterior of the plate being thus and thereby out of contact with the inner surface of the cylindrical body of the machine. Preparatory to starting the machine on the trimming operation, the stereotype plate is raised from the guides and is clamped

firmly and closely against the inner surface of the cylinder. After the plate is so clamped, the cylinder makes a rotation, and during such rotation the two ends of the 5 plate are carried past rotating saws, located at either end of the cylindrical body of the machine, and the head of the plate is thereby trimmed and the tail thereof is severed from the plate, and that end of the plate 10 also properly trimmed. At the same time, the concave back of the plate is carried past one or more fixed shaving knives, which shave the surface of the concave ribs on the back of the plate in a well known manner. 15 The plate is then unclamped, and as so finished or perfected drops to and rests on its straight edges upon the tracks or guideways within the machine body. It is then slid along the tracks or guideways out of the 20 machine, passing out in the same direction but at the opposite ends from which it came in. The plate is usually conveyed out of the trimming machine proper, as just described, by automatically operating mechanism, but 25 such mechanism is not shown or described in the present case, as any form of withdrawing means may be employed so far as the present invention is concerned.

The present invention as applied to such 30 a machine, relates primarily to the means and mechanisms for fastening or clamping the stereotype plate within the cylindrical body of the machine preparatory to and during the rotation of the machine past the 35 cutting and trimming and shaving devices which effect the finishing of the plate. The various features and constructions of this novel mechanism will be incorporated in the particular description of the illustrated embodiment, and there will be also pointed out 40 the cooperation of said mechanism with the means by which the plate carrying cylinder is started into rotation and whereby it is again brought to rest after the completion 45 of the trimming of the plate.

Referring now to the details of construction of the embodiment illustrated in the 50 accompanying drawings, a plate carrying cylinder 1 is arranged preferably horizontally, and is supported in a pair of annular frames or bearings 2 and 3, within which frames the cylinder is rotatable. The annular bearing frames 2 and 3 are mounted upon a suitable machine base 4. The track- 55 ways or guides 6 and 7 are arranged within and nearly centrally and longitudinally of the interior wall of the cylinder 1, very nearly a semi-circumference apart, so that as the plate α is slid into the machine, its 60 straight edges will rest upon and slide along the guides 6 and 7 with the convex character-bearing surface of the plate α out of contact with the interior of the cylinder 1.

The stereotype plates α are usually 65 pushed into the machine by the hands of

the operator, a suitable table or support being usually positioned in front of the machine to aid in this operation.

The embodied form of means for trimming the head and cutting off the tail of the plate α comprises rotary saws 10 and 11, at the opposite ends of the cylindrical body 1 of the machine, these saws being usually protected by casings. The saws 10 and 11 are fixed upon a shaft 12 mounted in bearings 13 and 14 carried upon the general machine. The shaft 12 is driven in any suitable manner, as by gear 15 driven by any suitable devices, not shown. 75

The shaving of the convex inner ribs of the stereotype plates is effected by one or more shaving knives or blades 16, indicated conventionally in the drawing. 80

A machine of the general type so far described is shown and described in Patent No. 1,126,741 to Wm. Evensen dated Feb. 2, 1915. 85

In the present preferred embodiment of the stereotype plate holding and clamping means, it is designed and constructed to operate in conjunction with the machine starting and machine stopping devices or mechanisms, that is the devices for starting and stopping the rotation of the cylinder 1 to effect the finishing of the plate and thereafter to leave it in position to be withdrawn or discharged upon the completion of the finishing operation. 90

In the embodied and exemplified form of means for rotating the cylinder 1, a gear ring 26 encircles the cylinder 1, and has fixed thereto a hub 25 carrying certain of the connections and controls for the operation of the cylinder 1 from the gear as will be later described. 100

The gear ring is loose on the cylinder and is driven by suitable means not shown. The gear ring 26 is connectable to and disconnectable from the cylinder 1, to effect the rotation of the cylinder together with effecting certain other functions, as will herein-after appear. 105

Referring now to the embodied form of plate clamping means, mechanism is provided adapted to engage with one of the straight edges of the plate, to lift it off the guide 6 or 7 and to press the plate firmly and solidly, and yet without too much pressure, against the interior of the cylinder 1. In accordance with the present invention 115 this means is controlled by the operator and is positive action. As embodied, one or more positively actuated clamping blocks 45 are provided, mounted on the cylinder 1 and located in breaks or interruptions in the guideway or track 6 or 7, and are slideable to and fro to clamp and to unclamp the plate. The clamping block 45 as shown has its upper surface even with or just below 120 the top of the track 7 while the plate is be- 130

- ing fed in, and is pressed upwardly by mechanism set in motion by the operator in starting the machine. In its upward movement it lifts the plate from track 7 (as shown in Fig. 2) and presses the plate against the interior of cylinder 1, preparatory to the finishing operation. Block 45 is moved downwardly automatically by the machine to free or unclamp the plate after the completion of the finishing operation, permitting its straight edge to rest upon the track or guideway 7, preparatory to the feeding out or discharge of the finished plate.
- As embodied, the clamping block 45 is fixed to a slide 46, and fixed to the slide 46 is a block 47, with which block the actuating means for the clamping device cooperates. Suitable supporting and guiding means for the members 45, 46 and 47 are provided, and as embodied guides or brackets 48 and 49 are mounted or supported upon the exterior of the cylinder 1 by suitable means such as screws 50, 51, 52 and 53. The slide 46 and actuating block 47 move to and fro within the guiding brackets 48 and 49, the clamp block 45 extending through a slot 54 into the interior of the cylinder 1 and into relation to the track-way 7 which has already been described.
- The actuating devices for the clamping block 45 and its slide 46 and actuating block 47 are also mounted in the guiding and supporting brackets 48 and 49. As embodied, a cam 55 of approximately somewhat more than semi-circular shape is adapted to engage with the actuating block 47 to slide the block in guides 48 and 49 to effect the movement of the clamping jaw 45 which has already been described. Fixed to cam 55 is a shaft 56, located substantially at one end of the flat or diametrical part of the cam. The shaft 56 is journaled in a cylindrical opening in the guide brackets 48 and 49. Fixed also to shaft 56, and if desired integral therewith is an actuating member 59, preferably of circular form. This member 59 is thus located just exteriorly to the supporting brackets 48 and 49. Journaled on the exterior side of the actuating member 59 is a contact or cam roller 60, located preferably a semi-diameter apart from the shaft 56. Certain parts of the mechanism, as will be later described, engage with the contact or cam roller 60 to impart rotative movement to the cam 55, and thereby give clamping and unclamping movement to the block 45.
- As embodied, and in accordance with certain features of the invention, a cam arm or actuating arm 61 is fixed to the starting rod 64. The cam starting arm 61 has an arcuate portion 62 upon the lower end thereof with which cooperates the roller 60. As the starting rod 64 is pushed to the right to the position shown in Fig. 2 the part 62
- of cam arm 61 will rotate roller 60 and therewith the cam 55 from the position shown in Figs. 4, 6, and 9 to that shown in Figs. 2, 3, 5, and 8, thereby causing the block 45 to clamp the plate α in the cylinder 70 1 as already described.
- In the embodied form of means for unclamping the plate such means operate automatically upon the completion of the trimming operation. Devices are provided upon the gear ring 25, or fixed thereto or moving or cooperating therewith, for engaging the cam roller 60 and reversing the movement effected through the cam arm 61 as already described, and thereby unclamping or releasing the plate preparatory to the discharge. That is, the mechanism is moved in the reverse direction, that is, counter-clockwise from the position of Figs. 2, 3, 5, 8 and 10 to that of Figs. 4, 6, 9 and 11. 75 80 85
- The embodied form of such mechanism is substantially the same or similar to that shown in the Evensen Patent No. 1,126,741 already referred to. As stated, gear ring 26 and its hub 25 are mounted upon and rotate loosely around cylinder 1. 90
- Cylinder 1 is normally held in plate-receiving position by a detent roller 65 (Fig. 2), carried on a bent lever 69, which lever is pivoted at 66 on the machine frame and 95 pressed by a spring 67. Roller 65 cooperates with a detent 68 formed on cylinder 1. The cylinder is thus positioned as shown in Fig. 2, with the guides 6 and 7 horizontal or level with respect to each other. Gear ring 26 100 thus rotates idly upon the cylinder 1 as a support, the cylinder being at rest.
- Pivoted at 71 on the hub 25 of gear ring 26 (Figs. 1, 2 and 12) is a detent 70, which is pressed inwardly by a spring 72, which 105 spring is mounted on hub 25. In the cylinder 1 (Fig. 12) is provided a recess 73, and lug 70 is pressed by spring 72 toward the left in Fig. 12 to engage recess 73 when passing by. 110
- If detent 70 did so engage with recess 73 it would lock cylinder 1 to gear ring 26 and cause them to rotate together. This is not desired, however, except when a plate is to be trimmed. 115
- Means are therefore provided for automatically swinging detent 70 backwardly, to the right in Fig. 12, so that it will miss recess 73 and cylinder 1 will be left stationary. Therewith are provided means whereby the operator can cause the detent 70 to lock in recess 73 and thereby effect a single revolution of cylinder 1 with gear ring 26. 120
- As embodied, a hook 75 is pivoted at 76 on the machine frame. Hook 75 is pressed inwardly into the path of detent 70 by a spring 77, which spring is mounted on the machine frame at 78 and has its free end pressing against the hook 75. The end 80 of hook 75 thus engages with and swings de- 125 130

tent 70 to the right against spring 72, causes it to escape recess 73, and cylinder 1 is left stationary as gear ring 26 rotates.

When the operator has put a plate in cylinder 1 and wishes to lock it in the manner described, and to then start the machine to trim and shave the plate, he pushes rod 64 against spring 83 to the right into the position shown in Fig. 2. This causes arm 61 to engage cam roll 60 and thereby clamps the plate α as already fully described.

The means for starting cylinder 1 is preferably actuated at the same time and by the same action of the operator. As embodied, 15 a cam 81 is fixed on starting rod 64 and the movement of rod 64 by the operator just described causes cam 81 to engage the top end 82 of lever 75, and to thereby swing lever 75 to the position shown in Fig. 12.

20 In this position of lever 75 it does not catch detent 70 and the detent, impelled by spring 72, engages recess 73, and cylinder 1 starts into rotation with gear ring 26, carrying the plate α past the trimming and shaving knives as already described. When cylinder 1 starts, the operator releases rod 64, which is then restored to the left by spring 83. On the next revolution, hook 75 catches 25 detent 70, cylinder 1 and gear ring 26 are disconnected, and cylinder 1 is stopped and positioned by detent roll 65.

The automatic means for unclamping plate α comprises a cam 85 fixed on hub 25 of the gear ring. This cam 85 engages cam 35 roll 60, rotates it in the counter-clockwise direction, and moves the plate clamping mechanism from the position of Figs. 2, 3, 5, 8, and 10 to the unclamped position of Figs. 4, 6, 9, and 11, which movements of 40 the clamping mechanism have already been described. It will be understood that when rod 64 was moved to the left by spring 83, arm 61 was thereby moved to the left away from cam roll 60, leaving it free to be moved 45 by cam 85 as just described.

The invention in its broader aspects is not limited to the details of construction shown and described, but departures may be made therefrom within the scope of the accompanying claims without departing from the principles of the invention and without sacrificing its chief advantages.

What we claim is:—

1. A stereotype plate finishing machine 55 including in combination a rotating plate carrier, means for holding the plate loosely therein, means including a cam for clamping the plate within the holder positively actuated by the hand of the operator.

60 2. A stereotype plate finishing machine including in combination a rotating plate carrier, means for holding the plate loosely therein, means for clamping the plate within the holder positively actuated by the hand 65 of the operator, said means including a plate

clamping member and an unyielding cam member engaging the clamping member to cause it to clamp the plate.

3. A stereotype plate finishing machine including in combination a rotating plate 70 carrier, means for holding the plate loosely therein, means for clamping the plate within the holder including a plate clamping member and a rotatable actuating member therefor unconnected thereto and in surface 75 contact therewith.

4. A stereotype plate finishing machine including in combination a rotating plate carrier, means for holding the plate loosely 80 therein, means for clamping the plate within the holder including a plate clamping member and an actuating cam engaging therewith to effect the clamping of the plate.

5. A stereotype plate finishing machine including in combination a rotating plate 85 carrier, means for holding the plate loosely therein, means for clamping the plate within the holder including a plate clamping member and an actuating cam engaging 90 therewith, and manually operated means for moving the cam to move the engaging member to clamp and unclamp the plate.

6. A stereotype plate finishing machine including in combination a rotating plate 95 carrier, means for holding the plate loosely therein, means for clamping the plate within the holder including a plate clamping member and an actuating rotatable cam engaging therewith.

7. A stereotype plate finishing machine 100 including in combination a rotating plate carrier, means for holding the plate loosely therein, means for clamping the plate within the holder including a plate clamping member and an actuating rotatable cam engaging therewith, and manually operated means for rotating the cam to move the engaging member to clamp and unclamp the plate.

8. A stereotype plate finishing machine 110 including in combination a rotating plate carrier, means for holding the plate loosely therein, means for clamping the plate within the holder positively actuated by the hand of the operator said means including a plate clamping member having translatory clamping movement and an unyielding cam engaging the clamping member to cause it to clamp the plate.

9. A stereotype plate finishing machine 120 including in combination a rotating plate carrier, means for holding the plate loosely therein, means for clamping the plate within the holder positively actuated by the hand of the operator said means including a plate clamping cam having translatory clamping movement and an unyielding rotatable member engaging the clamping member to cause it to clamp the plate.

10. A stereotype plate finishing machine 130

including in combination a rotating plate carrier, means for holding the plate loosely therein, means for clamping the plate with the holder including a plate clamping member having translatory clamping movement and an actuating member therefor unconnected thereto and in surface contact therewith.

11. A stereotype plate finishing machine including in combination a rotating plate carrier, means for holding the plate loosely therein, means for clamping the plate within the holder including a plate clamping member having translatory clamping movement and an actuating cam engaging therewith.

12. A stereotype plate finishing machine including in combination a rotating plate carrier, means for holding the plate loosely therein, means for clamping the plate within the holder including a plate clamping member having translatory clamping movement and a rotatable actuating cam engaging therewith.

13. A stereotype plate finishing machine including in combination a plate trimming cylinder, a clamp for clamping the plate within the cylinder, and a cam engaging with and moving the clamp to plate clamping position and means for causing said movement of the cam.

14. A stereotype plate finishing machine

including in combination a plate trimming cylinder, a clamp for clamping the plate within the cylinder, a cam engaging with and moving the clamp to plate clamping position, and manually operated means for positively moving the cam to cause the clamp to clamp the plate.

15. A stereotype plate finishing machine including in combination a plate trimming cylinder, a clamp for clamping the plate within the cylinder, a rotatable cam engaging with and moving the clamp to plate clamping position, and means for positively moving the cam to cause the clamp to clamp the plate.

16. A stereotype plate finishing machine including in combination a plate trimming cylinder, a clamp for clamping the plate within the cylinder, a cam engaging with and moving the clamp to plate clamping position, means for positively moving the cam to cause the clamp to clamp the plate, and automatically operating means for moving the cam to unclamp the plate.

In testimony whereof, we have signed our names to this specification, in the presence of two subscribing witnesses.

JOSEPH J. WALSER.
ALBERT A. HENZI.
